FUEL MIXING CHAMBER

John P. Harrison, Versailles, Ind.

Application October 7, 1948, Serial No. 53,295

3 Claims. (Cl. 48—180)

1.

My present invention relates to fuel mixing chambers and has for its object to provide a device which will more thoroughly mix liquid and gaseous fuels to bring about a more complete combustion of the mixture when used in internal combustion engines, heating devices or the like.

The consumption of high speed engines in use at the present time is so great that fuel from the carburetor is channelized at the core of the air stream resulting in a mixture which is richer in this channel and progressively leaner toward its periphery. As an example of this accelerated fuel demand it is appropriate to observe that a single cylinder four cycle engine operating at 3600 R. P. M. will have successive intake strokes at intervals of $\frac{1}{60}$ of a second. It is obvious that the limited amount of affinity between fuel and air requires too much time to effect a uniform mixture in the ordinary fuel line and since it is mechanically impractical to provide an intake pipe of an infinite length between the carburetor and engine there arises the necessity of producing a means of forcing such a mixture.

It is accordingly a further object of my invention to take the mixture as it comes from the carburetor and divide it so that part goes through one channel and the remainder through two other channels where it is finely divided by passing through many hundreds of orifices and so merged with the fuel in the first channel.

Another object of my present invention is to produce an efficient gas mixing chamber which is compact in design thereby occupying a minimum of space in the mechanical apparatus with which it may be used.

Still other objects and advantages will become apparent from the following description of the present invention illustrated in the accompanying drawing in which:

Figure 1 is a plan view of the device.

Figure 2 is an enlarged sectional view taken on line 2—2 of Fig. 1, the coacting parts of the carburetor and intake manifold being shown fragmentarily.

Figure 3 is a partial plan view of one of the perforated mixing plates.

Similar reference characters in the several figures indicate similar parts.

Referring first to Fig. 2 of the drawing, 1 indicates a pipe leading from a carburetor or mixing valve (not shown) which supplies a combustible mixture to the intake manifold 2 of an internal combustion engine or heating device.

Conveniently located between the pipe 1 and manifold 2 is a mixing chamber 3 provided with

a shallow cylindrical body portion 4 and a mating circular cover 5. A circular horizontal flange 6 is located at the top of the body 4 and cooperates with a groove formed on the inner face of the cover 5 to hold a gasket 7 forming an air tight seal when the body and cover are rigidly joined by a plurality of metal rivets 8 passing through aligned apertures 9 uniformly distributed around the peripheries of the cover and the body flange 6.

A boss 10 formed on the outer face of the cover 5 is provided with a pair of threaded holes 11 to receive connecting bolts 12. These bolts pass through apertures 13 carried by an abutment flange 14 on the end of the carburetor outlet or pipe and by such means the mixing chamber assembly is rigidly fixed to the carburetor. A similar attaching arrangement is provided at the opposite end of the mixing chamber for securing the boss 15 on the body to a flange 16 located on the intake manifold of the engine.

Suspended within the above described casing, by means of spacer posts 17, is a circular mixing plate or disc 18 which cooperates with the inner surface 19 of the cover to form a radial channel 20. The channel 20 is sealed at its periphery by a ring flange 21 projecting from the face of the cover 5 a distance equal to the length of the posts 17. The ring 21 performs a dual purpose in that it also provides one face of the angular groove 20 mentioned above as the recipient of body flange 6.

The mixing plate 18 contains a central aperture 22 aligned with and of equal diameter to an intake throat 23 in the cover. The plate is further provided with an infinite number of small orifices 24 positioned in a staggered arrangement so that any part of a stream of fuel mixture moving radially from the center of the chamber toward the outer edge of the channel 20 will have to pass some of these orifices.

I locate a plurality of supporting posts 25 on the inner surface 26 of the body member. These supports are of greater length than the posts 17, previously mentioned and have fixed to their upper ends an impervious disc 27 which coacts with the surface 26 of the body to form a radiating discharge channel 28. This channel surrounds the outlet, or throat 29 in the boss 15 of the chamber body.

Secured to the periphery of the upper surface of the disc 27 is a ring-shaped spacer 30 which carries a second mixing plate 31 spaced equidistantly between the plate 18 and disc 27. The mixing plate 31 cooperates with plate 18 and disc 27 to respectively define radiating channels 32

and 33. The channel 32, which for the purpose of illustration, may be termed the intermediate channel, is open at its lower peripheral edge and discharges into a vertical cylindrical passageway 34 defined by the rim 35 of the body 3 and the ring-shaped spacer 30. The passageway 34 it will be observed is also a continuation of the outer circular edge of the aforementioned discharge channel 28.

The channel 33 being sealed at its periphery by the spacing ring 30 has for its outlet an infinite number of orifices 36, similar in plan to the aforementioned orifices 24. Mixing plate 31 likewise has a central aperture 37 which assists the corresponding aperture of plate 18 in outlining a well-like extension of the intake throat 23, the bottom of which is defined by the disc 27.

In determining the vertical depth of the three radiating channels as viewed in Fig. 2, the co-operating surfaces of the elements are so spaced that the combined cylindrical inlet areas of the channels as defined by the intersection of the channels and the central well will be equal to the cross sectional area of the inlet throat.

The orifices 24 and 36 are preferably of small diameter and numerous in quantity so as to provide each mixing plate with a more effective fuel dividing operation. The total combined area of the orifices 24 and 36 is immaterial as long as the minimum number in such area provide an ample discharge of the fuel metered by their respective channels. Thus, if a carburetor having a 1½ inch throat is used the minimum number of orifices of .04 inch diameter in each mixing plate will be 491, making a total of at least 982 orifices spraying into the intermediate channel. It will of course be understood that the number of spraying orifices may be further increased thereby increasing the effectiveness of the mixing plates.

Since the area of channel 32 progressively increases from the center, it will be seen that it thus accommodates additional fluid as injected from the outer channels by the orifices. The passageway 34 and discharge channel 28 are accordingly of sufficient cross sectional area thus accommodating the combined output of the three metering channels 29, 32 and 33.

In the operation of the device the mixture from the carburetor is drawn through the throat 23 into the central well formed by the apertures in the mixing plates. The mixture then takes three separate routes. A part flows through the intermediate channel, defined by the plates 18 and 31, and that remaining is divided between the two outer channels 29 and 33. Thence the fluid is forced through the infinite number of interstices 24 and 36 which causes it to be finely divided and sprayed into the intermediate stream in channel 32 for thorough mixing with such stream. The effectively mixed fuel then flows through the passageway 34 into the discharge channel 28 from which it is fed to the intake manifold of the engine.

From the foregoing description of the present invention, it will be seen that by the use of profusely perforated plates set in spaced relation to each other I am able to divide the carburetor mixture into separate streams of which the outermost is sprayed back into the intermediate stream for complete mixing. The structure presents a compact and effective device for providing an internal combustion or heating apparatus with thoroughly comminuted and mixed fuel for economic and efficient operation.

While a preferred form of the invention has

been shown and described, it will be understood that variations in details of form may be made without departure from the invention as defined in the appended claims.

5 I claim:

1. A device for mixing fuel comprising a casing having an end wall and an inlet opening substantially centrally located in said wall, said casing also having an outlet opening; a first plate, a second plate and an imperforate disc all parallel to said wall and successively spaced therefrom and from one another to form parallel channels between the wall and the first plate, between the plates and between the second plate and the disc; each of said plates having a central aperture in alignment with the inlet opening and each also having a multiplicity of small orifices surrounding the aperture; means radially exterior of the orifice in said first plate closing the channel between said wall and said first plate; means radially exterior of the orifices in said second plate and enclosing the channel between said plate and said disc, said disc and the wall of the casing opposite the aforementioned end wall forming at least in part a channel for conducting mixed fuel from the channel between said plates to said outlet; whereby fuel is taken in through the inlet opening and the fuel from the channels between the wall and the first plate and between the second plate and the disc are injected into the fuel in the channel between the plates by way of said orifices and the mixture is discharged through the outlet opening.

2. A device for mixing fuel comprising a casing having an end wall and an inlet opening in said wall, said casing also having an outlet opening; a first plate, a second plate and an imperforate disc all substantially parallel to said wall and successively spaced therefrom and from one another to form substantially parallel channels between the wall and the first plate, between the plates and between the second plate and the disc; each of said plates having a central aperture in substantial alignment with the inlet opening and each also having a multiplicity of small orifices surrounding the aperture; means radially exterior of the orifices in said first plate closing the channel between said wall and said first plate; means radially exterior of the orifices in said second plate and closing the channel between said plate and said disc, said disc and the wall of the casing opposite the aforementioned end wall forming at least in part a channel for conducting mixed fuel from the channel between said plates to said outlet; whereby fuel is taken in through the inlet opening and the fuel from the channels between the wall and the first plate and between the second plate and the disc are injected into the fuel in the channel between the plates by way of said orifices and the mixture is discharged through the outlet opening.

3. A device for mixing fuel comprising a casing having an end wall and an inlet opening in said wall, said casing also having an outlet opening, a first plate, a second plate and an imperforate disc all substantially parallel to said wall and successively spaced therefrom and from one another to form substantially parallel channels between the wall and the first plate, between the plates and between the second plate and the disc; each of said plates having a central aperture in substantial alignment with the inlet opening and each also having a multiplicity of small orifices surrounding the aperture; means radially exterior of the orifices in said first plate closing the

channel between said wall and the first plate; means radially exterior of the orifices in said second plate and closing the channel between said second plate and said disc, said casing having passage means therein for conducting mixed fuel from the channel between said plates to said outlet; whereby fuel is taken in through the inlet opening and the fuel from the channels between the wall and the first plate and between the second plate and the disc are injected into the fuel in the channel between the plates by way of said orifices, and the mixture is discharged through the outlet opening.
